CLAIM

I claim, the ornamental design for a syringe handle, as shown and described.

DESCRIPTION

FIG. 1 is a perspective view of a first embodiment of a syringe handle, showing my new design;
 FIG. 2 is a front elevational view thereof;
 FIG. 3 is a rear elevational view thereof;
 FIG. 4 is a right side elevational view thereof;
 FIG. 5 is a left side elevational view thereof;
 FIG. 6 is a top plan view thereof;
 FIG. 7 is a bottom plan view thereof;
 FIG. 8 is a front perspective view of a second embodiment of a syringe handle, showing my new design;
 FIG. 9 is a front elevational view thereof;
 FIG. 10 is a rear elevational view thereof;
 FIG. 11 is a right side elevational view thereof;
 FIG. 12 is a left side elevational view thereof;
 FIG. 13 is a top plan view thereof; and,
 FIG. 14 is a bottom plan view thereof.

The broken lines in FIGS. 1-14 are for the purpose of illustrating portions of the syringe handle and environmental structure that form no part of the claimed design.
